UNITED STATES PATENT OFFICE.

JOHN D. MILLER, OF WASHINGTON, DISTRICT OF COLUMBIA, ASSIGNOR OF ELEVEN-SIXTEENTHS TO FIRMAN R. HORNER, ALLEN S. JOHNSON, AND JERRY F. RITTER, OF SAME PLACE.

DESIGN FOR A MILK-JAR.

SPECIFICATION forming part of Design No. 30,431, dated March 28, 1899.

Application filed March 3, 1899. Serial No. 707,679. Term of patent 14 years.

To all whom it may concern:

Be it known that I, JOHN D. MILLER, a citizen of the United States, residing at Washington, in the District of Columbia, have invented and produced a new and original Design for Milk-Jars, of which the following is a specification, reference being had to the accompanying drawings, forming part thereof.

Figure 1 is a front elevation of a milk-jar, showing my new design. Fig. 2 is a top plan view of the same. Fig. 3 is a section on the line xx , Fig. 2, the body of the jar being broken away.

As shown in the drawings, the leading or material feature of my design consists of a lug or projection 1, extending upwardly from the top and bottom of the top of the jar and

around the mouth of the jar about three-quarters of the circumference of said mouth, the remaining circumference 2 being on a lower plane than the top of said lug or projection, as more clearly shown in Fig. 3, the said lug or projection being undercut or dovetailed, as at 3, thereby forming a groove in the inner face of said lug or projection.

Having described my invention, what I claim as new, and desire to secure by Letters Patent, is—

The design for a milk-jar, as herein shown and described.

JOHN D. MILLER.
